CLAIM

The ornamental design for a whirlpool bathtub, as shown and described.

DESCRIPTION

FIG. 1 is a top, front perspective view of a whirlpool bathtub showing my new design;

FIG. 2 is an inverted top plan view thereof on an enlarged scale;

FIG. 3 is a rear elevational view thereof on an enlarged scale;

FIG. 4 is a side elevational view thereof on an enlarged scale, the opposite side being a mirror image;

FIG. 5 is a front elevational view thereof on an enlarged scale;

FIG. 6 is a bottom plan view thereof on an enlarged scale;

FIG. 7 is a cross-sectional view thereof as taken along line 7—7 of FIG. 1 on an enlarged scale;

FIG. 8 is a cross-sectional view thereof as taken along line 8—8 of FIG. 1 on an enlarged scale;

FIG. 9 is a cross-sectional view thereof as taken along line 9—9 of FIG. 2;

FIG. 10 is a cross-sectional view thereof as taken along line 10—10 of FIG. 2;

FIG. 11 is a top, front perspective view of a second embodiment of my new design;

FIG. 12 is an inverted top plan view thereof on an enlarged scale;

FIG. 13 is a cross-sectional view thereof as taken along line 13—13 of FIG. 12;

FIG. 14 is a cross-sectional view thereof as taken along line 14—14 of FIG. 12.

The front, rear and sides of the second embodiment are substantially identical to those of the first embodiment.

FIG. 1**FIG. 2****FIG. 3****FIG. 4****FIG. 5****FIG. 6****FIG. 7****FIG. 8****FIG. 9****FIG. 10**FIG. 11

FIG. 12

FIG. 13

FIG. 14
